FUR AND WOOLEN COLD STORAGE COMPARTMENT FOR HOUSEHOLD REFRIGERATORS

Candace Baird Alig, Des Moines, Iowa

Application October 9, 1935, Serial No. 44,227

2 Claims. (Cl. 62—89)

An object of my invention is to provide a fur and woolen cold storage compartment of simple, durable and inexpensive manufacture for a household refrigerator.

5 A further object is to provide a cold storage compartment mounted in the same casing as a food compartment of a refrigerator but the cold storage compartment being independent of the food compartment and having an independent

10 cooling unit.

A further object is to provide a cold storage compartment having a cooling unit which can be operated from the same refrigerating machine which operates the cooling unit of the food com-

15 partment of the refrigerator, means being pro-

vided to shut off the cooling unit in the cold storage compartment when it is not needed.

Another object is to provide a cold storage compartment for fur and woolen clothing and the like having a cooling unit adjacent the floor of 20 the compartment so that condensate does not drop therefrom on to the articles of clothing, as would be the case if the cooling unit were mounted adjacent the top of the compartment as in the usual food refrigerator arrangement.

25 Another object is to provide a small air circulating fan to insure circulation of air in the cold storage compartment and thereby insure that the entire volume of air within the compartment will be at the same temperature.

Another object is to provide in the cold storage compartment a rod for coat hangers and the like and hooks for articles of clothing or any suitable means for supporting coats and the like within the compartment and out of contact with the cooling unit.

Another object is to provide a grating over the cooling unit to prevent any possibility of the articles of clothing contacting with the cooling unit.

40 With these and other objects in view my invention consists in the construction, arrangement and combination of the various parts of my device, whereby the objects contemplated are attained, as hereinafter more fully set forth, pointed out in my claims and illustrated in the accompanying drawing in which:

Figure 1 is a perspective view of a refrigerator showing a pair of doors open, one door being for 45 a food compartment of the refrigerator and the other for my fur and woolen cold storage compartment.

50 Figure 2 is a vertical sectional view on the line 2—2 of Figure 1; and

55 Figure 3 is a horizontal sectional view on the

line 3—3 of Figure 1 showing an air circulating fan to prevent stratification of air within the cold storage compartment and thereby insure an even temperature throughout the compartment.

On the accompanying drawing I have used the 5 reference numeral 10 to indicate generally a refrigerator casing. The casing 10 is provided with a pair of compartments A and B. These are normally closed by doors 12 and 14 respectively in the usual manner of providing closures for 10 refrigerator food compartments. The walls of the compartments A and B are suitably insulated against the entrance of heat, the insulation being shown in Figures 2 and 3 at 16.

Within the compartment B I provide a cooling 15 unit 18 which is preferably mounted adjacent the floor of the compartment. Adjacent the top of the compartment I provide a coat hanger rod 28 on which a plurality of hangers 22 may be hooked. In Figure 1 I show a fur coat 24 and an over-coat 26 hung on the hangers 22 and also another 20 article of clothing, such as a wool skirt 28, hung on one of the hooks 30, which I provide projecting from the wall of the compartment for this purpose.

25 The cooling unit 18 is located adjacent the floor rather than adjacent the top as is the cooling unit 32 for the food compartment A so that condensate dripping therefrom will not fall on and injure the articles of clothing within the cold storage compartment B.

30 I further protect the articles of clothing against contact with the cooling unit 18 by a grating 34 which is positioned thereover.

35 The necessity of locating the unit 18 adjacent the floor of the compartment B brings up the problem of air stratification because the air cooled by the unit would have a tendency to stay adjacent the unit and the air within the compartment would be progressively warmer, the warmest air, of course, being at the top of the compartment. The unit 32 produces thermal air circulation, but that is not possible when the unit is mounted adjacent the floor. Accordingly, I provide a very small electric fan 36, the motor of 45 which is indicated at 38. This is preferably positioned under the grating 34 and at one end of the cooling unit 18. A plurality of deflector blades 40 are provided so as to deflect the air and evenly distribute it over the cooling unit 18. 50

55 The air is drawn downwardly as indicated by the arrow a and then deflected as indicated by the arrow b, whereupon it passes over the cooling unit 18 and then upwardly as indicated by the arrow c. Thus air circulation is effectively pro-

duced and since the velocity of movement need be only minute, the motor 38 can be of very small size and therefore economically operated.

A cold temperature can be economically maintained in a cold storage compartment of the character I have disclosed and the articles of clothing are always instantly available, as contrasted with the expense and bother of having furs and woolens stored at centralized cold storage plants.

10 In the winter time, if it is desirable not to use the cold storage compartment, the cooling unit 18 can be rendered inoperative by closing control valves 42 and 44, thus shutting off the flow of refrigerant to and from the refrigerating unit

15 (not shown), which then supplies refrigerant to the food compartment unit 32 only. It is obvious, of course, that the cooling unit 18 can be operated whenever the cooling unit 32 is operated so that a separate control switch need not be 20 provided responsive to the temperature in the compartment B. If desired, however, a control switch can be provided responsive to this temperature.

25 Below the cooling unit 18 I provide a defroster pan 48 which is readily removable and provides for collection of condensate from the cooling unit if it becomes necessary to defrost it.

Some changes may be made in the construction 30 and arrangement of the parts of my device without departing from the real spirit and purpose of my invention and it is my intention to cover by my claims any modified forms of structure or use of mechanical equivalents which may be reasonably included within their scope.

I claim as my invention:

1. In a device of the class described, a refrigerator casing, a food compartment therein and a fur and woolen cold storage compartment therein and independent of said food compartment, a 5 cooling unit for said food compartment and a second cooling unit for said fur and woolen cold storage compartment, said second cooling unit being positioned adjacent the bottom of said fur and woolen cold storage compartment, a grating 10 over said second cooling unit and means for circulating the air within said last mentioned compartment past said second cooling unit.

2. In a device of the class described, a refrigerator casing, a food compartment therein and a fur and woolen cold storage compartment therein and independent of said food compartment, a cooling unit for said food compartment and a second cooling unit for said fur and woolen cold storage compartment, said second cooling unit 15 being positioned adjacent the bottom of said fur and woolen cold storage compartment, a grating over said second cooling unit, means for circulating the air within said last mentioned compartment past said second cooling unit, said 20 means comprising a fan located beneath said grating and at one end of said second cooling unit, said fan being operable to circulate air downwardly through said grating over said cooling unit and then upwardly through said grating, a 25 distributor adjacent said fan to evenly distribute the air over the cooling unit and a removable tray below said cooling unit to catch condensate therefrom.

CANDACE BAIRD ALIG. 35
